UNITED STATES PATENT OFFICE

2,160,602

DISPENSER

William F. Nagel, Clermont, Fla., assignor to The
Air Konditioning Company, Clermont, Fla., a
corporation of Florida

Application March 10, 1937, Serial No. 130,019

5 Claims. (Cl. 65—45)

This application is a continuation in part of my co-pending application for United States Letters Patent, Serial No. 40,383, filed September 13, 1935.

5 This invention relates to improvements in dispensers for hydrophilic materials such as salt or the like, and refers specifically to a dispenser so constructed that the hydrophilic material during 10 or the dispensing operation passes through channels or passageways formed in a dispenser head constructed of a material having relatively great affinity for water or moisture.

Although my invention is adaptable for the dispensing of any type of material displaying a 15 high degree of affinity for moisture, for purposes of description, it will be described in conjunction with its use as a salt server, shaker or cellar.

One of the most annoying and exasperating situations which is tolerated day in and day out, 20 arises in the dispensing of salt at certain periods from the commonly used salt cellar or shaker. During damp weather it is a common experience to have the salt cake in the dispenser or have it accumulate in a moist condition at the lower 25 face of the dispenser head where it effectively blocks the usually small dispensing openings.

The usual perforated dispensing head is invariably the seat of the difficulty. Such heads are frequently constructed of metal or some such 30 material having a relatively high degree of heat conductivity which is conducive to moisture condensation, and in substantially all cases the head is non-absorbent to moisture. Consequently, at the location where the salt or other 35 dispensed material encounters the most difficulty in flowing, because of the relatively small perforations, it is most apt to encounter moisture, both conditions conspiring to prevent the convenient dispensing of the salt or other material.

40 My invention is particularly directed to a construction which is adapted to cure the defects above mentioned, and contemplates the provision of a shaker or dispenser head constructed of a material having a relatively great 45 affinity for moisture, that is, the material is characterized both by its moisture absorbent properties and also its properties of relatively low heat conductance. The head is so constructed that the dispensed material, salt for 50 instance, when the dispenser is inverted, contacts the absorbent material comprising the head, and in addition, the dispensing openings or apertures comprise channels or bores through the thickness of the absorbent material comprising 55 the head. Thus, upon inverting the dispenser a

large mass of the salt or other contents of the dispenser not only comes into contact with the head, but the material comprising the head defines the channels or bores through which the salt or other contents is dispensed. Obviously, 5 therefore, at or adjacent the zone where the caking or wetting of the salt or other contents would be most annoying or disadvantageous to convenient dispensing, a material is situated (the material comprising the head) which is conducive to the removal or absorption of the moisture. Therefore, under extremely humid conditions, seldom met with in practice, caking of the salt will never take place at the place where it would do most harm, that is, adjacent the head 10 or dispensing openings.

Other objects and advantages of my invention will be apparent from the accompanying drawing and following detailed description.

In the drawing,

Fig. 1 is a side elevational view of a dispenser, parts being broken away and parts being shown in section.

Fig. 2 is a fragmentary view of a modified form of dispenser head.

Figs. 3, 4, 5, 6 and 7 are similar views of various modifications, illustrating different means of securing to the dispenser body.

Referring in detail to the drawing, 1 indicates a conventional condiment dispenser or shaker 30 which may comprise a body 1, constructed of glass, china or other material conventionally used for such purposes, and a dispensing head 3 which comprises an embodiment of my invention. Of course, the body 2 of the dispenser may take 35 any desired shape or form so long as it is capable of carrying a dispensing head constructed in conformity with my invention. The head 3 may be constructed of any material which possesses water absorbent or so-called drying materials, 40 such as diatomite, various earths, clays, calcium salts or the like. The material is preferably of relatively small particle size and may, if necessary, be mixed with a binder whereby the head may be pressed, molded or otherwise formed to 45 suitable shape and proportions.

The head 3 is adapted to be mounted at the open mouth of the container 2, and is held in desired position by means of an annular collar 4 which may be constructed of metal, "Bakelite", 50 hard rubber or other suitable material. The lower portion of the collar 4 is formed to provide threads 5 which engage with cooperating threads formed adjacent the mouth of the container 2. The upper portion of collar 4 is in- 55

wardly turned to provide an annular flange or shoulder 6 which engages with the top of the head 3. At an intermediate portion of the head 3 shoulders are formed which are adapted to 5 engage with a retainer 7 which in turn rests upon the defining edge of the mouth of the container, the retainer, when the collar is screwed in place upon the mouth of the container, being adapted to confine the head 3 and hold the same 10 against the flange 6.

The head 3 is provided with a central bore or channel 8 which establishes communication between the interior and exterior of the container. As a feature of my invention, the head 3 is constructed of a drying material or a material having a high affinity for moisture and by the provision of the bore 8 the salt or material to be dispensed passes through said bore. The head per se comprises considerable volume of drying material and in addition is so constructed that, when the container is inverted, a considerable area of said head contacts the salt or other contents of the container. In addition, the salt in being dispensed must pass through the bore and, hence, 20 substantially all of the individual particles of salt dispensed must at some period during the dispensing operation contact the material comprising the head. Obviously, the opportunity for a transfer of moisture from the salt or other contents of the container to the head is a maximum, and dispensing difficulties due to caking or blocking at the dispensing opening are reduced to a 25 minimum.

Further, at any given time a more or less small 30 volume of air is maintained in the container 2. This air must of necessity enter the container through the bore 8 which is of relatively restricted diameter. Hence, the opportunity for a moisture transfer from the air so entering the container and the head 3 is also a maximum. Although I realize that the moisture absorbing capacity of the head 3 is not unlimited, the periods of excessive humidity encountered are of relatively short duration and are balanced by interspersed periods of reduced humidity. I have found that, considering average humidity conditions, the presence of the head 3 at the strategic position, as it were, adjacent the dispensing end of the container functions to maintain the body 40 of salt within the container drier than would ordinarily be the case. This coupled with the fact that the salt, during dispensing, actually contacts the material of the head in a more or less dispersed condition, that is, with respect 45 to the small cross-section of flowing salt which is permitted to pass through the channel 8, materially reduces the possibility of caking of the salt or other contents of the dispenser or the blocking 50 of the dispensing openings.

55 The head of my dispenser, of course, may take many different forms, but in substantially all cases the volume of the material comprising the head is relatively large as compared with the volume of the metal or other materials heretofore used for dispenser heads. In addition, the 60 length of the channels comprising the dispensing openings is relatively great so that a relatively great opportunity is provided for the contact of the salt or other contents of the container and 65 head material.

In Figs. 2, 3, 4, 5, 6 and 7 a few modified forms of such dispensing heads are shown.

Referring particularly to Fig. 2, the reference numeral 9 indicates a conventional condiment 70 container having a neck portion 10 defining its

mouth. An annular collar 11 being provided with threads 12 adjacent its lower end is adapted to be mounted upon the neck 10, the threads 12 being engageable with threads formed upon said neck. A dispenser head 13 constructed of material of a similar nature to the material comprising head 3 is adapted to be confined within the collar 11 and is retained within said collar by means of retainer 14 which rests upon the upper defining edge of the neck 10. The head 13 is provided with a bore or channel 15 through which the salt or other material carried within container 9 may be dispensed.

In Fig. 3, 15 indicates a fragmentary portion of a container for salt or the like, having a neck portion 16 provided with external threads which are adapted to be engageable with threads 17 formed on the lower portion of an annular collar 18. The upper portion of the collar 18 is bent inwardly to form an angularly disposed annular flange which is adapted to confine or retain a dispenser head 19 constructed of a material similar to the heads 3 and 13. The upper portion of the head 19 is of frusto-conical shape and terminates at its lower portion in cylindrical shape. The lower cylindrical portion of the head 19 is of restricted diameter with respect to the upper conical portion thereof and is adapted to fit within the neck 16 of the container 15. Retainers 20 are positioned at the upper edge of the neck 16, whereby the head 19 is securely held within the collar 18. The head 19 is provided with a central bore or channel 21 through which the salt may be dispensed upon inverting the container 15.

In Figs. 4, 5, 6 and 7, heads are shown which may be mounted upon or over the mouth of containers. In Fig. 4, 22 indicates a salt container, for instance, having a neck portion 23, the external surface of which is provided with threads. A head 24 constructed of moisture absorbent material hereinbefore described is formed in the shape of a paraboloid. An annular recess 25 is provided in the lower portion of the head 24 and is defined by an annular outer wall 26, the internal surface of which is provided with threads which engage with the threads upon the external surface of the neck 23. The head 24 is provided with a central channel or dispensing opening 27. It can readily be seen that in this construction the head is of unitary integral form and requires no separate securing means.

In Fig. 5, 28 indicates a container having a neck 29, the internal surface of said neck being provided with threads which engage threads 30 formed on the restricted lower portion of a dispensing head 31. The dispensing head 31 resembles the head 24 in shape. However, the head 31 is provided with threads 30 which are adapted to engage internal threads of the neck 29 as opposed to the external engagement of the head 24 with the neck 23. The head 31 is provided with one or more dispensing channels or openings 32, any number of which is contemplated.

Referring particularly to Fig. 6, 33 indicates a container having a restricted neck 34 upon which a dispensing head 35 is mounted. The lower portion of the dispensing head 35 is recessed, said recess being defined by the annular walls 36 which are adapted to make frictional engagement with the external surface of the neck 34. The head 35 is provided with a central aperture 37 through which the salt may be dispensed.

In Fig. 7, 38 indicates a conventional container

having a neck 39. A head 40 is adapted to be mounted upon or over the mouth of the container 38 and is recessed annularly as indicated at 41 at its lower portion. The restricted lower portion 5 42 of the head 40 is adapted to frictionally engage the inner surface of the neck 39. Head 40 is provided with one or more dispensing apertures or channels 43, any number of which are contemplated. It is of course to be understood that the 10 heads 24, 31, 35 and 40 are constructed of a material of similar nature to that constituting heads 3, 13 and 19. The basic material comprising the heads 24, 31, 35 and 40 is characterized by its high absorptivity.

15 It will be noted that in all of the forms illustrated and described a limited quantity of salt or contents of the container contacts a maximum area of the dispenser head when the container is inverted. In addition, the volume of each head is 20 relatively large so that ample moisture absorbing capacities may be obtained. Further, the defining walls of the dispensing openings comprise the absorptive material, providing for more intimate contact between the individual particles of 25 salt and the absorptive material whereby a more efficient moisture transfer is obtained. A still further characterizing feature of all of the heads resides in the fact that provision is made for a relatively large area of contact between the atmosphere and contents within the containers.

30 It is to be understood, of course, that the head of the dispenser may take any desired form or shape. Accordingly, I do not wish to be limited to the specific modifications illustrated and described since they are merely exemplary of forms which can be conveniently used.

I claim as my invention:

1. In combination, a dispenser for finely divided material susceptible to caking or sticking 40 when and after being exposed to moisture comprising a container having a mouth, a dispensing head forming a closure for said mouth, said dispensing head being constructed of a hygroscopic material, said head being provided with a channel 45 affording communication between the interior and exterior of said container, whereby upon inverting said container contact is afforded between the material of the head and the material to be dispensed.

50 2. In combination, a dispenser for finely di-

vided material susceptible to caking or sticking when and after being exposed to moisture comprising a container having a mouth, a dispensing head forming a closure for said mouth, said dispensing head being constructed of a hygroscopic 5 material, said head being provided with an elongated channel affording communication between the interior and exterior of said container, whereby upon inverting said container a relatively large degree of contact is afforded between the material 10 of the head and the material to be dispensed.

3. In combination, a dispenser for finely divided material susceptible to caking or sticking when and after being exposed to moisture comprising a container having a mouth, a dispensing head forming a closure for said mouth, said dispensing head of relatively great volume being constructed of a hygroscopic material, said head being provided with a channel affording communication between the interior and exterior 15 of said container whereby upon inverting said container a relatively large degree of contact is afforded between the material of the head and the material to be dispensed.

4. In combination, a dispenser for finely divided material susceptible to caking or sticking when and after being exposed to moisture comprising a container having a mouth, a dispensing head forming a closure for said mouth, said dispensing head being constructed of a hygroscopic 25 material, said head being provided with a channel affording communication between the interior and exterior of said container, the area of 30 the head exposed to the interior of the container being at least a substantial part of the cross-sectional area of the mouth of the container, whereby upon inverting said container contact is afforded between the material of the head and the material to be dispensed.

40 5. In combination, a dispenser for finely divided material susceptible to caking or sticking when and after being exposed to moisture comprising a container having a mouth, a cap forming a closure for said mouth, said cap comprising 45 a hygroscopic material, said cap also being provided with an opening affording a communication between the interior and exterior of the container.

WILLIAM F. NAGEL. 50
